FLUE STRUCTURE FOR GAS RANGES

Herman A. Davidson, Detroit, Mich., assignor to
Aveo Manufacturing Corporation, a corpora-
tion of Delaware

Application June 7, 1946, Serial No. 675,068

11 Claims. (Cl. 126—39)

1

The invention relates to cooking ranges and more particularly to flue structures for venting the products of combustion from the broiler and oven compartments of the range.

One object of the invention is to provide a flue structure for venting hot air or gases from the broiler compartment and oven compartments which includes a flue inside of the structural wrapper of the range, and which baffles radiated heat, decreases the wall-temperature, and eliminates restriction of secondary air to the top burner box.

Another object of the invention is to provide a flue structure of this character which is simple in construction, adapted to be readily assembled with the wrapper and liners for the cooking compartments, and which may be economically fabricated.

Other objects of the invention will appear from the detailed description.

The invention consists in the several features hereinafter set forth and more particularly defined by claims at the conclusion hereof.

In the drawings:

Fig. 1 is a vertical longitudinal section taken on line 1—1 of Fig. 2 of a cooking range embodying the invention.

Fig. 2 is a vertical transverse section taken on line 2—2 of Fig. 1.

Fig. 3 is a perspective of the structural wrapper and the flue structure attached thereto.

Fig. 4 is a perspective of the liner for the baking compartment.

Fig. 5 is a perspective of the liner for the broiler compartment.

Fig. 6 is a sectional perspective illustrating the flue structure at the back of the baking compartment and the stack for hot air and gases.

Fig. 7 is a sectional perspective of the structural wrapper and the flue embodied therein.

Fig. 8 is a section taken on line 8—8 of Fig. 1.

Fig. 9 is a vertical section of a modified form of the invention.

The invention is exemplified in a range of the cabinet type and which includes a structural wrapper, a top burner box, *a*, over the wrapper, a broiler compartment *b* within said wrapper and below the top-burner box at one side of the cabinet, a baking compartment *c* at the opposite side of the cabinet within the wrapper.

The body structure comprises a wrapper of sheet metal, generally designated 20, which functions as an integral structural bottom, top and back. Wrapper 20 includes a bottom-wall 21, a

back-wall 23, and a top-wall 22, all of which are integrally formed of a single sheet of metal. The broiler compartment *b* and the baking compartment *c* are disposed inside of the wrapper. 5 The front margins of the top and bottom walls of the wrapper are rigidly vertically connected by posts 26. Top-wall 22 of wrapper 20 forms the bottom of the top-burner box or compartment *a*. Panels 27 of sheet metal form lower structural elements at the ends of the wrapper. A base panel 30 structurally connects the front ends of panels 27. Insulated end-panels 29 are secured to inturned flanges on wrapper 20, for closing the ends thereof. Channel bars 31 are secured on 10 top of the ends of top-wall 22 of wrapper 20 and form the ends of the space above the wrapper, which extends over compartments *b* and *c*. A front panel 33 extends between and is secured to bars 31 for closing the space which includes the 15 top-burner compartment *a* above wrapper 20.

An aeration pan 35 which extends over the burner box is supported over the top-burner compartment by one of the end panels 31 and a central transverse bar 32 which is supported on the 20 top of the wrapper. A lid 37 is suitably hinged to the range-body and is adapted to cover the exposed portions of the burners in box *a*. Burners *d* are suitably supported in the top-burner box. A panel 39 closes the top of the space over the wrapper 20 at the right hand side of the body. A splashback 41 of sheet metal is supported on brackets 52 which are secured to the channel bars 31.

The broiler compartment *b* is provided with a liner 43 which includes a top-wall 44, side-walls 45, and a back-wall 46. A hinged door *e* forms the front of compartment *b* and provides for access thereto. A burner *f* is suitably supported inside of compartment *b*. The baking compartment is provided with a liner 47 which includes a top-wall 49, side-walls 50, and a back-wall 51. A hinged door *g* forms the front of the baking compartment and provides for access thereto. A suitable burner *h* and bottom are provided for compartment *c*. Liner 43 of the broiler compartment is supported vertically by a transverse bar 53 and a transverse plate 54 which are rigidly secured to the body-structure. Liner 47 for the baking compartment is supported vertically by a 30 fixed transverse bar 52 and one of the lower-end panels 27.

A flue structure is provided for venting the compartments *b* and *c*. This structure comprises a flue 57 in the upper rear corner of wrapper 20, which is formed by said wrapper and a wall, in-

cluding a vertical portion 58 which has its upper end flanged and welded to the inner face of the top-wall 22 of said wrapper and a lower rearwardly and downwardly inclined portion 59 which has its lower margin welded to the wrapper, and walls 60 which close the ends of said flue. Flue 57 is provided with an opening 63 for receiving hot air and gases from an opening 67 in the back of the liner for the broiler compartment b, and an opening 64 for receiving hot air and gases from an opening 75 in the back of the liner for the baking compartment c. The upper rear corner of the baking compartment liner 41 is provided with an inset or recess consisting of and conforming to and spaced from flue walls 58 and 59 formed by a vertical wall portion 73 and an inclined wall portion 74. The vertical wall portion 73 of the back of the oven liner is provided with the opening 75 adapted to communicate with opening 64 in the flue wall 58. The back-wall 51 of the baking compartment liner is spaced from the back-wall 23 of wrapper 20 and the liner is so secured by spacers 69 which are secured by bolts to the back-wall 23 of wrapper 20.

The upper rear corner of the liner for the broiler compartment b is provided with a transverse inset or recess conforming to and spaced from the vertical and inclined portions 58, 59 of flue 57, being formed by a vertical upper wall portion 65 and a rearwardly and downwardly inclined wall portion 66. Wall portion 65 is provided with the opening 67 which registers with the opening 63 in the flue wall 58.

A packing 71 of asbestos rope fits between the flue-wall 58 and the wall-portion 73 around communicating openings 64 and 75 for reducing heat transfer between the flue wall and the baking compartment liner at the openings. A similar packing 71 is interposed between the back-wall portion 65 and flue-wall 58 for reducing heat transfer between the broiler compartment liner and the walls of flue 57. The back-wall portion 46 of the broiler compartment liner is also supported in spaced relation from back-wall 23 of wrapper 20 by spacers 70 which are secured by bolts to said back-wall 23.

A stack 79 for venting air or gases from flue 57 is mounted on and supported from the portion of back of the wrapper which is disposed rearwardly of the baking compartment. The hot air and gases pass into said stack through an opening 80 in the upper rear corner of said wrapper. This stack is formed of side-walls 81, a back-wall 82, a front-wall 83, and an inclined top-wall 84. In the inclined front-wall 83 and below top-wall 84, an opening is formed for venting the gases from the stack 79 through horizontal slots 87 in the front-wall of the splashback 41. The lower end of stack 79 is open to permit air in back of wrapper 20 to flow into said stack which receives the hot air and gases from the broiler compartment liner 43 and the baking compartment liner 41. Insulating material 86, such as asbestos rope, is interposed between the stack around its opening which communicates with slots 87 for reducing heat transfer to the splashback 41.

Air for supporting combustion at the burner for the baking compartment c and the burner for broiler compartment b enters wrapper 20 through openings 90 and 91. The hot air and gases from the broiler compartment are vented through openings 67, 63 into the flue 57 in the upper rear corner of the wrapper, and the hot air and gases from the baking compartment are vented through

openings 75, 64 into the flue 57. From flue 57 the hot air and gases are vented through opening 80 in the upper rear corner of wrapper 20 into stack 79 from which they escape through slots 87 in the front of the splashback. The insets extending across the upper rear liners baffle the radiated heat in the liners and make it possible to provide a flue in the wrapper having sufficient area to reduce the wall temperature in the flue. Hot air and gases passing through the upper portion of stack 79 draw unheated air from the back of the wrapper through the open lower end of the stack to cool the hot air and gases discharged from the stack.

The rear of the top burner box below the aeration pan 35 is open for free entry of secondary air to the top burner box. Stack 79 being disposed in horizontal offset relation with respect to the burner box, it causes no restriction of the flow of secondary air to said box.

In the modification illustrated in Fig. 9, a stack 93 is secured to the upper rear corner of wrapper 20 at the rear of the baking compartment and the gases are discharged from the stack into an exhaust flue 94. This construction is usable when the gases are not exhausted from the stack through the splashback or the range is not provided with a splashback.

Advantageous characteristics of the venting structure described are that the flue 57 is disposed within the structural wrapper 20; and the broiler compartment liner 43 and baking compartment liner 41 are recessed for the disposal of flue 57 within the wrapper; the back-walls of the liners are spaced from the walls of flue 57 and back-wall 23 of wrapper 20 and insulation is provided around the communicating openings between the liners and said flue. The hot air and gases are vented from the upper rear corner of the wrapper into the stack 79 into which cool air from the back of the wrapper passes to cool the hot air and gases before they are discharged from the stack. The insets in the liners baffle radiated heat and the flue has sufficient area for decreasing the temperature of the walls of the flue and the wrapper. The flue structure produces no restriction in the flow of secondary air to the top burner box; is simple in construction, and can be fabricated at a low cost.

The invention is not to be understood as limited to the details described, since these may be modified within the scope of the appended claims, without departing from the spirit and scope of the invention.

Having thus described the invention, what I claim as new and desire to secure by Letters Patent is:

1. A range comprising a pair of liners for separate cooking compartments, each including a back and a top, a surrounding wall extending around the top and back of both of said compartments, a top-burner box overlying the top of the surrounding wall said wall being spaced from said liners at the rear and top of said liners and providing an air chamber between said liners and said wall, a structure for venting said compartments disposed in said air chamber forming a cross-flue on the inside of the upper rear corner of the surrounding wall; the back of the liners and the cross-flue having openings communicatively connecting the compartments and the cross-flue, and an upwardly extending flue on the outside of the surrounding wall communicating with the cross-flue, said surrounding wall form-

ing a wall common both to said cross-flue and said upwardly extending flue.

2. A range comprising a pair of liners for separate cooking compartments, each including a back and a top, a surrounding wall extending around the top and back of both of said compartments and spaced therefrom, a top-burner box overlying the top of the surrounding wall, a structure for venting said compartments disposed in the space between said liners and said surrounding wall, forming a cross-flue on the inside of the upper rear corner of the surrounding wall, the liners being spaced from the top and back of the surrounding wall, means communicatively connecting the compartments and the cross-flue, and an upwardly extending outlet flue on the outside of the surrounding wall communicatively connected to the cross-flue, said surrounding wall forming a wall common both to said cross-flue and said upwardly extending flue.

3. A range comprising a pair of liners for separate cooking compartments, each including a back and a top, a surrounding wall extending around the top and back of both of said compartments and spaced therefrom, a top-burner box overlying the top of the surrounding wall, a structure for venting said compartments disposed in the space between said liners and said surrounding wall, forming a cross-flue on the inside of the upper rear corners of the surrounding wall, the back of the liners and the flue having openings communicatively connecting the compartments, and the cross-flue, insulation around said openings, and an upwardly extending flue on the outside of the surrounding wall communicating with the cross-flue, said surrounding wall forming a wall common both to said cross-flue and said upwardly extending flue.

4. A range comprising a pair of liners for separate cooking compartments, each including a back and a top, a surrounding wall extending around the top and back of both of said compartments and spaced therefrom, a top burner box overlying the top of the surrounding wall, a structure for venting said compartments disposed in the space between said liner and said surrounding wall, forming a cross-flue on the inside of the upper rear corner of the surrounding wall, the back of the liners and the cross-flue having openings communicatively connecting the compartments and the cross-flue, the surrounding wall having an outlet in its upper rear corner, and an upwardly extending flue on the outside of the surrounding wall, communicating with said outlet, and in back of and above one of the compartments, said surrounding wall forming a wall common both to said cross-flue and said upwardly extending flue.

5. A range comprising a pair of liners for separate cooking compartments, each including a back and a top, a surrounding wall extending around the top and back of both of said compartments and spaced therefrom, a top-burner box overlying the top of the surrounding wall, a structure for venting said compartments disposed in the space between said liners and said surrounding wall, forming a cross-flue on the inside of the upper rear corner of the surrounding wall, the back of the liners and the cross-flue having openings communicatively connecting the compartments and the flue, the surrounding wall having an outlet in its upper rear corner, and an upwardly extending flue on the outside of the surrounding wall, communicating with said outlet, disposed in back of one of the compartments,

and having an open lower end for the entry of air at the back of the surrounding wall, said surrounding wall forming a wall common both to said cross-flue and said upwardly extending flue.

5. 6. A range comprising a liner for a cooking compartment, including a back and a top, a surrounding wall extending around the top and back of and spaced from the liner, a top-burner box overlying the top of the surrounding wall, the liner having an inset at its upper rear corner, a structure for venting the compartment, forming a flue inside of the upper rear corner of the surrounding wall and extending into the inset, the liner and the structure having means communicating with the compartment and the flue, the surrounding wall having an outlet in its upper rear corner, and an upwardly extending flue on the outside of the surrounding wall and communicating with said outlet.

10. 7. A range comprising a liner for a cooking compartment, including a back and a top, a surrounding wall extending around the top and back of and spaced from the liner, a top-burner box overlying the top of the surrounding wall; the liner having an inset at its upper rear corner, a structure for venting the compartment, forming a flue inside of the upper rear corner of the surrounding wall and extending into the inset, means communicating with the compartment and the flue, insulation means around said connecting means, the surrounding wall having an outlet in its upper rear corner, and an upwardly extending flue on the outside of the surrounding wall and communicating with said outlet.

15. 8. A range comprising a liner for a cooking compartment, including a back and a top, a surrounding wall extending around the top and back of and spaced from the liner, a top-burner box overlying the top of the surrounding wall, the liner having an inset with a vertical portion and an inclined lower portion at its upper rear corner, a structure for venting the compartment, forming a flue inside of the upper rear corner of the surrounding wall and extending into the inset, means communicating with the compartment and the flue, the surrounding wall having an outlet in its upper rear corner, and an upwardly extending flue on the outside of the surrounding wall and communicating with said outlet.

20. 9. A range comprising a liner for a cooking compartment, including a back and a top, a surrounding wall extending around the top and back of and spaced from the liner, a top-burner box overlying the top of the surrounding wall, the liner having an inset with a vertical portion and an inclined lower portion at its upper rear corner, a structure for venting the compartment, forming a flue inside of the upper rear corner of the surrounding wall and extending into the inset, means communicating with the compartment and the flue, the surrounding wall having an outlet in its upper rear corner, and an upwardly extending flue on the outside of the surrounding wall and communicating with said outlet.

25. 10. A range comprising a pair of liners for separate cooking compartments each including a back and top, a surrounding wall extending around the top and back of both of said compartments, a top burner box overlying the top of the surrounding wall, a housing disposed intermediate

30. 75.

said liners and said surrounding wall, said housing having a portion thereof secured to the top of said surrounding wall and another portion thereof secured to the rear of said surrounding wall, said surrounding wall and said housing enclosing a cross-flue for venting both of said cooking compartments, openings in said housing communicatively connecting the compartments and said cross-flue, an outlet in said surrounding wall in communication with said cross-flue, and a vertically disposed upwardly extending flue on the side of said surrounding wall opposite said housing in communication with said outlet, said surrounding wall forming a wall common to both said cross-flue and said vertical flue.

11. A range comprising a pair of liners for separate cooking compartments each including a back and top, a surrounding wall spaced from said liners extending around the top and back of both compartments, a top burner box overlying the top of said surrounding wall, a housing disposed in the space intermediate said liners and said surrounding wall, said housing including an upwardly extending portion spaced from the rear of said surrounding wall secured to the under-surface of the top of said surrounding wall and a rearwardly extending portion spaced from the

top of said surrounding wall and secured to the rear of said surrounding wall, said housing and said surrounding wall enclosing a cross-flue for venting both of said compartments, openings in said housing communicatively connecting the compartments and cross-flue, an outlet in said surrounding wall, and a vertically disposed upwardly extending flue on the rear wall of said surrounding wall opposite said housing communicating with said outlet, said surrounding wall forming a wall common to both said cross-flue and said vertical flue.
